UNITED STATES PATENT OFFICE.

CARL J. HAGSTROM, OF GLEN COVE, NEW YORK.

LOCKING MECHANISM FOR DOUBLE DOORS AND WINDOWS.

1,094,143.

Specification of Letters Patent. Patented Apr. 21, 1914.

Application filed April 11, 1913. Serial No. 760,336.

To all whom it may concern:

Be it known that I, CARL JOHN HAGSTROM, a citizen of the United States, residing at Glen Cove, Long Island, in the county of 5 Nassau and State of New York, have invented certain new and useful Improvements in Locking Mechanism for Double Doors and Windows; and I do hereby declare the following to be a full, clear, and 10 exact description of the invention, such as will enable others skilled in the art to which it appertains to make and use the same, reference being had to the accompanying drawings, and to characters of reference 15 marked thereon, which form a part of this specification.

The present invention has reference, generally, to improvements in locking mechanism for doors, windows and similar places; 20 and the invention relates, more particularly, to an improved construction of combination latch and lock-mechanism for doors, French casement windows.

The said invention has for its principal 25 object to provide a novel, simple and efficient construction of combined lock and latch mechanism operating at three points of the door or casement window, viz. at the top, bottom, and stile of the door or casement, the three bolts or latches operating 30 to hold the door or casement window at the said three points, being simultaneously controlled by the operation of a single handle or knob. By thus holding the doors or casement windows at the said three points in 35 closed relation to the frame, the same are prevented from warping, and are securely and firmly held in closed position.

Another object of the present invention 40 is to provide a key-lock controlled means for coupling or uncoupling the operative relation of the outside handle or knob devices with the latch-mechanisms, whereby when said handle or knob device is uncoupled, the spring-latches cannot be withdrawn, by the turning of the handle or knob, from their closed or engaged relation 45 with the receiving sockets of the striking plates with which they coöperate, and consequently are under such conditions practically fulfilling the functions of a dead-lock bolt.

Other objects of this invention not at this time more particularly enumerated will be

clearly evident from the following detailed 55 description of the said invention.

With the various objects of the present invention in view, the same consists, primarily, in the novel construction of combination lock and latch-mechanism hereinafter 60 set forth; and, the invention consists furthermore, in the novel arrangements and combinations of the various devices and parts, as well as in the details of the construction of the same, all of which will be 65 hereinafter more fully described, and then finally embodied in the clauses of the claim which are appended to and which form an essential part of this specification.

The invention is clearly illustrated in the 70 accompanying drawings, in which:—

Figure 1 is a face view of a French casement window with the meeting-stiles thereof shown in section to illustrate embedded therein the novel construction of combined 75 latch and lock-mechanism made according to and embodying the principles of the present invention. Fig. 2^a is a detail vertical section taken on line 2^a—2^a in said Fig. 2. Fig. 2 is a detail view, enlarged, of said novel combined latch and lock mechanism with the casings open to show the interior construction of operating mechanism, the part being shown in normal or latching position; and Fig. 3 is a similar view, except that the 85 parts are shown in operated or unlatching position. Fig. 4 is a detail longitudinal section taken on line 4—4 in said Fig. 2, looking in the direction of the arrow *x*. Fig. 5 is a detail section taken on line 5—5 in said Fig. 90 4, looking in the direction of the arrow *y*, and providing a view of the interior combination latch and lock-mechanism, the same illustrating the key-lock controlled mechanism thereof about to actuate the means for 95 uncoupling the outside or knob device from the latch or bolt-mechanism, so as to render said handle or knob device inoperative from the outside of the door; and Fig. 6 is illustrative of said key-lock controlled mechanism 100 after its actuation resulting in said uncoupling operation. Fig. 7 is a detail view of the tumbler actuated by said key-lock controlled mechanism about to be thrown by said key-lock controlled mechanism into operative engagement with the coupling tumbler, said view being a section taken on line 105 7—7 in said Fig. 4, looking in the direction

- of the arrow z , and said view corresponding in time of operation to said Fig. 5; and Fig. 8 is a similar view corresponding in time of operation to said Fig. 6. Fig. 9 is a detail section taken on line 9—9 in said Fig. 4, and illustrating a spring-controlled means for returning the handle and knob mechanism to normal position after operation. Fig. 10 is a detail section through the casing taken on line 10—10 in said Fig. 2, and illustrating in elevation the coupling means connected with said handle or knob members and the coupling tumbler in operative relation thereto.
- 15 Similar characters of reference are employed in all of the hereinafter described views, to indicate corresponding parts.
- Referring now to the said drawings, the reference-characters 1 and 2 indicate the respective members of a French casement window which are hinged by their outer stiles to the vertical members 3 of the casement frames. The novel combined latch and lock-mechanism made according to and embodying the principles of the present invention is illustrated in said Fig. 1 of the drawings as embedded in the respective meeting styles 4 and 5 of said casement members 1 and 2. The mechanism connected with said meeting stile 4 of the casement member 1 comprises a lock-casing 6, provided with a longitudinal end-plate 7 having an opening 8. This end-plate 7 is exposed flush with the meeting surface or edge of said meeting stile 4. Movably arranged within the interior of said lock-casing 6 is a latch-member 9, the operative chamfered end 10 of which projects, normally, through said opening 8 in said end-plate 7. Arranged between the inner end of said latch-member 9, and one wall of said lock-casing 6, are spring-members 11 which maintain said latch-member 9 in its normally outwardly thrust or projecting position.
- 45 Rotatably mounted in a suitably disposed opening in one side wall of said lock-casing 6 is a hub or barrel 12 from which extends an annular rib or projection 13, a portion of which is cut away to provide a receiving socket 14. Said hub or barrel 12 is provided with an axially disposed opening 15, preferably of rectangular cross section. Rotatably mounted in a suitably disposed opening in the opposite side wall of said lock-casing 6 is another hub or barrel 16, the same registering in alignment end to end with said first-mentioned hub or barrel 12, the inner end of said hub or barrel 16 projecting into a receiving portion in the inner end of said hub or barrel 12, so as to be journaled therein, and so as to maintain the respective hubs or barrels in their registered and aligned relation one to the other, but each being capable of rotation independently of the other. Extending laterally from said hub or barrel 16

is a lug or tongue 17, and said hub or barrel 16 is further provided with an axially disposed opening A, preferably of rectangular cross section.

The reference-character 18 indicates a handle or knob which is journaled in a bearing-plate 19 secured to the inner side of the said meeting stile 4. Connected with said handle or knob 18 is a shank-member 20, one end of which is adapted to be received in said axial opening 15 of said hub or barrel 12, so that when said handle or knob 18 is turned said hub or barrel 12 is likewise rotated therewith. The reference-character 21 indicates a handle or knob which is journaled in a bearing-plate 22 secured to the outer side of the said meeting stile 4. Connected with said handle or knob 21 is a shank-member 23, one end of which is adapted to be received in said axial opening A of said hub or barrel 16, so that when said handle or knob 21 is turned said hub or barrel 16 is likewise rotated therewith. The respective inner ends of said respective shank-members 20 and 23 are joined together by a screw-shank and screw-socket connection 24, whereby the said shanks are capable of independent rotation to actuate the respective hubs or barrels with which they are connected, but owing to such connection 95 cannot be pulled apart axially, to permit the withdrawal of either of said handle or knobs 18 or 21 from their operative assembled relation to said hubs or barrels and said meeting-stile 4 as above described.

Suitably located adjacent to the upper end of the inner longitudinal end wall of said lock-casing 6 is a socket member 25 in which is fulcrumed one end of a coupling tumbler 26, said socket-member 25 being so formed as to permit a longitudinal downward movement of said coupling tumbler 26 as well as a forward swinging movement of the same. The said coupling tumbler is cut away at its free end at 27 to permit the same to straddle said lug or tongue 17 of said hub or barrel 16, so that the coupling-pin or projection 28 at the extreme end of said coupling tumbler will lie, normally, between said lug or tongue 17 and the end of said annular rib or projection 13 of said hub or barrel 12, so as to be engaged by said lug or tongue 17 when said hub or barrel 16 is rotated, and thus transmit the movement of the latter to said hub or barrel 12 by forcing the end of said tumbler 26 against the end of said rib or projection 13. A spring member 29 is connected with said coupling tumbler 26 so as to maintain said coupling-pin or projection 28 in operative relation with said hubs or barrels 12 and 16 in the manner above described. When the coupling tumbler 26 is thus normally arranged, by turning the outside handle or knob 21 the barrel or hub 16 is rotated which carries 130

5 said lug or tongue 17, which forms a part thereof, into engagement with said coupling-pin or projection 28 forcing the latter into engagement with the end of said annular 10 rib or projection 13, so that as the barrel or hub 16 rotates its lug or tongue 17 presses against said coupling-pin or projection 28 carrying the same downward, and thus causing a downward movement of said coupling-tumbler 26, the upper end of which slides in the receiving-socket 25, as shown in Fig. 3 of the drawings. This downward movement of the coupling-tumbler 26 permits the coupling-pin or projection 28 to press against 15 said annular rib or projection 13 of the hub or barrel 12 thereby causing the latter to rotate, said coupling-pin or projection 28 being maintained in engagement with said annular rib or projection 13 of the hub or 20 barrel 12 by reason of the spring action of said spring-member 29, which causes an outward swinging of said coupling-tumbler 26 simultaneously with its downward movement, and in this manner the rotary movement of said handle or knob 21 and hub or barrel 16 is transmitted to the hub or barrel 12, which by its rotation causes the actuation of the catch-mechanism coupled therewith.

30 Connected with, and extending laterally from, said hub or barrel 12 is a cam-arm 30, the free end of which engages operatively a tail-projection 31 which extends downwardly from one side of the inner end of 35 said latch-member 9, so that when said hub or barrel 12 is rotated the cam-arm 30 moves against said tail-projection and withdraws inwardly said latch-member 9 from its normal position, and against the tension of the 40 spring 11. As an aid in returning said hub or barrel 12 and said cam-arm 30 to its normal initial position, after actuation, there is provided a spring-member 32, one end of which is anchored to a wall of said lock-casing 6, and the free end of which operatively engages said hub or barrel 12.

45 Pivotaly mounted upon a fulcrum-post 33, connected with one side wall of said lock-casing 6, is a lever-member 34. Pivotaly 50 connected with one end of said lever-member 34 is a connecting-link 35, the opposite end of which is pivotally connected with an outwardly projecting arm 36 which also forms a part of said hub or barrel 12. Also 55 extending outwardly from said opposite or lower end of said connecting-link 35 is a lug or projection 37. Pivotaly connected with the free end of said lug or projection 37 is a pull-piece 38, the free end of which is 60 notched, as at 39, to receive a correspondingly notched coupler 40, which is connected with a connecting-rod 41. The said connecting-rod 41 extends downwardly through a suitable longitudinal passage provided in 65 said meeting-stile 4.

Countersunk in the lower end of said meeting-stile 4 is a latch-casing 42, the cover-member 43 of which is provided with an opening 44 through which projects the chamfered nose 45 of the cylindrical body 46 of a latch-member. The inner end 47 of said latch-casing 42 is cylindrical in form to slidably receive said cylindrical body 46, and a coil-spring 48 is arranged between the end of said inner end 47 and said cylindrical body 46, to normally maintain said latch-member in outwardly projecting position with its nose received in the opening of a striking-plate 49 secured to the sill 50 of the casement-frame. Connected with the cylindrical body of said latch-member is a tail-piece 51 provided with an eye-member 52 in which is inserted the connecting-arm 53 of a slide-piece 54, the latter being mounted slidably in a bearing-piece 55 secured in said meeting-stile 4, said bearing-piece 55 having a slot 56 through which said connecting-arm 53 extends. The said connecting-rod 41 is operatively secured to said slide-piece 54. In like manner, pivotally connected with the other end of said lever-member 34 is a pull-piece 57, the free end of which is notched, as at 58, to receive a correspondingly notched coupler 59, which is connected with a connecting-rod 60, the latter extending upwardly through a suitable longitudinal opening in said meeting-stile 4, and connecting with a latch-mechanism 61 of the same general construction above described, as connected with said connecting-rod 41. Said latch-mechanism operates in conjunction with a striking-plate 62 secured in the transom 63 of said casement frame.

60 As will be well understood from an inspection of the drawings, particularly Figs. 2 and 3, when said barrel or hub 12 is rotated and said latch-member 9 is withdrawn from its casement-closing position, as above described, the arm 36 of said hub or barrel 12 simultaneously operates through the above described lever system and connecting-rods to withdraw the latch-mechanism at the upper and lower ends of the casement window, from their respective holding engagements with said striking-plates 49 and 65 62, respectively, of the sill 50 and transom 63 of the casement-frame, thus permitting the casement, which by said mechanism is latched at three points, to be opened when the three latches are thus simultaneously released or withdrawn.

65 It will be understood from an inspection of the accompanying drawings that, so long as the coupling-pin or projection 28 of the coupling-tumbler 26 remains in normal coupling contact or engagement between the rib or projection 13 and lug or tongue 17 of the respective hubs or barrels 12 and 16, the latch-mechanisms above described may be 70 75 80 85 90 95 100 105 110 115 120 125 130

operated by turning either the inside handle or knob 18, or the outside handle or knob 21. But if said coupling-tumbler 26 is withdrawn so as to withdraw said coupling-pin 5 or projection 28, as shown in Fig. 6 of the drawings, then said outside handle or knob 21 will rotate said barrel or hub 16 without transmitting said movement to the barrel or hub 12, and consequently the casement 10 window is locked from the outside, and can only be opened, that is the latch-mechanisms can only be withdrawn, by turning the inside handle or knob 18.

In order to effect the disengagement or 15 removal of said coupling tumbler 26 from its normal coupling relation to said hubs or barrels 16 and 12, there is provided a key-lock controlled mechanism operable by a key from the outerside of said casement window 20 to actuate the tumbler throwing means, and a knob-controlled connection operable from the inner side of the casement window for also controlling the tumbler-throwing means. This mechanism is constructed and 25 operates as follows:—Rotatably mounted, so as to extend through the inner side of said meeting-stile 4, is the shank 64 of a knob 65. Rotatably mounted by its hub-portion 66, which is journaled in a suitably 30 disposed opening in the inner side wall of said lock-casing 6, is an oscillating-cam 67, the same being secured to said shank 64 of said knob 65. Said oscillating-cam 67 is provided with a nosing 68 which is engaged 35 by a flat spring 69, in such a manner, that said spring 69 maintains said oscillating-cam in either of its thrown or oscillated positions. Extending outwardly from the body of said oscillating cam 67 are properly disposed cam-projections 70 and 70', so positioned with relation to each other as to provide an intervening space 71. Stop-pins 72 and 73 are mounted upon the wall of said lock-casing 6 and are respectively engaged 40 by the shoulders 74 and 75 formed in said oscillating-cam 67 according into which of its positions the same is thrown. By properly turning the said knob 65 said oscillating-cam 67 is turned or oscillated to carry 45 its cam-projection 70 into contact with said coupling-tumbler 26 thereby swinging the latter backward upon its fulcrum and carrying its coupling-pin 28 away from its operative engagement and association with said 50 respective hubs or barrels 16 and 12. Said oscillating cam-member is retained in this holding relation to said coupling-tumbler 26 by the action of the spring 69 until the same is again turned in the opposite direction, whereupon the coupling tumbler 26 55 will be released so that it may be returned by its spring-member 29, and thus again carry into operative association with said hubs or barrels 12 and 16 its coupling-pin 60 28. It will thus be apparent, that by thus

actuating said tumbler disengaging means by turning the knob 65 on the inside of the casement window, that the outside handle or knob 21 is rendered inoperative with relation to the latch mechanisms and means for withdrawing the same, and consequently the latches serve as bolts to lock the casement window against opening from the outside. In order to permit the opening of the casement window from the outside, when in such locked condition, there is provided a key-lock mechanism comprising, a lock-body 76 which is mounted so as to extend through the outer side of said meeting stile 4 and through the outer wall of said lock-casing 6, and to then register in position above said oscillating cam 67. Rotatably mounted in said lock-body 76 is a key-barrel 77, the rotation of which is controlled by a suitable key-member 78 adapted to be inserted therein. Secured to the inner end of said rotatable key-barrel in any suitable manner is a tumbler 79. This tumbler 79 is set to be eccentric in its movement with relation to said oscillating-cam 67; consequently, when 70 said rotatable key-barrel 77 is turned by the key 78 the tumbler 79 passes into said intervening space 71 between the cam-projections 70 and 70', and if the oscillating cam 67 is set so that the cam-projection 70 75 is in holding engagement with said coupling-tumbler 26, said tumbler 79 is turned so as to pass into said intervening space 71 and engage the end of said cam-projection 70' pushing against the same and thereby oscillating said oscillating cam 67 to carry the same around and remove said cam-projection 70 from such holding relation with said coupling tumbler 26. In so doing, the nosing 68 of said oscillating cam 67 is turned 80 past the dead center of the spring-pressure of the spring 69, so that the spring 69 operates to complete the return oscillation of said oscillating cam 67 until the latter engages the stop-pin 72, and said tumbler 79 85 passes out of said intervening space 71 and away from engagement with said cam-projection 70', to its normal initial position. If the oscillating cam 67 is out of engagement with said coupling tumbler 26, and it 90 is desired to withdraw said coupling tumbler 26 from coupling relation to said hubs or barrels 12 and 16 by engaging said oscillating-cam 67 therewith, after closing the casement window from the outside, and thus 95 render the outside handle or knob 21 inoperative and the casement window locked, the key 78 is inserted in said lock-body 76 and said key-barrel 77 is turned in the opposite direction. This operation carries said tumbler 79 into said intervening space 71 and into engagement with said cam-projection 70 of said oscillating-cam 67, thus 100 oscillating the latter, and turning said cam-projection 70 into holding and removing en- 105

110

115

120

125

130

gagement with said coupling tumbler 26, the nosing 68 of said oscillating-cam 67 being again carried past the dead center of spring-pressure of the spring 69, so that the spring 69 operates to complete the movement of 5 said oscillating-cam 67, and the said tumbler 79 passes out of said intervening space 71, and away from contact with the cam-projection 70, thus passing back to its normal 10 position so that the key-member 78 may be withdrawn.

In order to further assist the said handle or knob 21, and said hub or barrel 16, and parts operated thereby, to return to normal 15 position after actuation the following device is provided: Countersunk in the inner side of said meeting-stile 4 and secured in a stationary position, is a bearing-member 80 provided with a chambered portion 81. 20 Journaled in said bearing-member is a rotatable element 82 having a perforated lug 83 to which is connected one end of a pull-spring 84, the other end of the latter being anchored to a transverse pin 85 passing 25 through said chamber 81. Said rotatable element 82 is provided with an axially disposed opening through which passes the shank 23 of said handle, said opening corresponding to the rectangular cross-section of 30 said shank. Thus, when the handle or knob 21 and shank 23 are turned, the rotatable element 82 is also turned, thereby putting said pull-spring 84 under tension, which, when said handle or knob 18 is released, tends to 35 pull or return the latter, by operation upon said rotatable element 82 and shank 23, to its normal initial position.

Connected with, and embedded within said meeting stile 5 of the casement member 2, is 40 a casing 86, provided with a longitudinal end-plate forming a striking-plate 87, and having an opening 88 adapted to receive the nosing of said latch-member 9 of the latch-mechanism connected with the meeting-stile 45 4 of the adjoining casement member 1. This striking-plate 87 is exposed flush with the meeting surface or edge of said meeting stile 5. Rotatably mounted between the side walls of said casing 86 is a hub or barrel 89 50 from which projects an arm 90. Said hub or barrel 89 is provided with an axially disposed opening 91, preferably of rectangular cross section, the same being adapted to receive the shank 92 of handles or knobs 93, 55 so that by turning the latter said hub or barrel is rotated. If desired the handle or knob 93 may be arranged to project only on the inner side of the casement member 2, and may be eliminated from the outer side thereof. 60 Pivotaly mounted upon a fulcrum post 33' connected with one side wall of said casing 86 is a lever-member 34'. Pivotaly connected with one end of said lever-member 34' is a connecting-link 35', the opposite end 65 of which is pivotaly connected with said

arm 90 of the hub or barrel 89. Also extending outwardly from said opposite or lower end of said connecting-link 35' is a lug or projection 37'. Pivotaly connected with the free end of said lug or projection 70 37' is a pull-piece 38', the free end of which is notched, as at 39', to receive a correspondingly notched coupler 40' which is connected with a connecting-rod 41'. The said connecting-rod extends downwardly through a 75 suitable longitudinal passage provided in said meeting-stile 5 and in the lower end of which is a latch-casing 42', the cover-member 43' of which is provided with an opening 44' through which projects the chamfered nosing 45' of the cylindrical body 46' of a latch-member. The inner end 47' of said latch-casing 42' is cylindrical in form to slidably receive said cylindrical body 46', and a coil-spring 48' is arranged between the 80 end of said inner end 47' and said cylindrical body 46' to normally maintain said latch-member in outwardly projecting position with its nosing received in the opening of said striking-plate 49 secured to the sill 50 85 90 of the casement frame. Connected with the cylindrical body of said latch-member is a tail-piece 51' provided with an eye-member 52' in which is inserted the connecting arm 53' of a slide-piece 54', the latter being 95 mounted slidably in a bearing-piece 55' secured in said meeting-stile 5, said bearing-piece 55', having a slot 56' through which said connecting-arm 53' extends. The said connecting-rod 41' is operatively secured to 100 said slide-piece 54. In like manner, pivotaly connected with the other end of said lever-member 34' is a pull-piece 57', the free 105 end of which is notched, as at 58', to receive a correspondingly notched coupler 59' 110 which is connected with a connecting-rod 60', the latter extending upwardly through a suitable longitudinal opening in said meeting-stile 5, and connecting with a latch-mechanism 61' of the same general construction above described as connected with said connecting-rod 41'. Said latch-mechanism operating in conjunction with said striking-plate 62 secured in the transom 63 of said casement frame. A spring-member 94 is 115 connected to one end of said lever-member 34' and its other end anchored to some stationary point within said casing 86, the same serving to return the above described parts 120 to their normal initial position after actuation.

As will be apparent the above described latch-mechanism serves to hold the casement member 2 at the top and bottom thereof in latched engagement with the casement 125 frame, and at the same time provides a striking-plate and latch receiving portion for the latch-member 9 operatively associated with the meeting-stile 4 of the casement member 1. It will also be apparent 130

that by operating the handle or knob 93 both of said latch-mechanisms operated by the interconnecting lever-system may be withdrawn simultaneously from their latched relation to said casement-frame.

From the above description the novel construction of combined latch and lock mechanism and operating means, together with its mode of operation will be readily understood.

I am fully aware that some changes may be made in the arrangements and combinations of the various devices and parts, as well as in the details of the construction of the same, without departing from the scope of the present invention as set forth in the foregoing specification, and as defined in the claims which are appended thereto. Hence, I do not limit my invention to the exact arrangements and combinations of the devices and parts as described in the said specification, nor do I confine myself to the exact details of the construction of the said parts as illustrated in the accompanying drawings.

I claim:—

1. The combination with the meeting stile of a door or window of a main casing, a spring thrown latch member mounted in said main casing, a rotatable means in said main casing, a cam arm on said rotatable means adapted to engage the tail of said latch-member, a handle-mechanism for actuating said rotatable means; vertical latch mechanism mounted at the ends of said meeting stile, each comprising a casing, a spring projected latch-body mounted therein, and an inwardly extending tail-piece, a lever-member pivotally mounted in said main casing, pull-pieces connected with opposite ends of said lever-member, an arm on said rotatable means interconnected with said lever-member for oscillating the same, and connecting-rods, said connecting-rods interconnecting said tail-pieces of said vertical latch mechanism with said pull-pieces of said oscillatable lever-arm.

2. The combination with the meeting stile of a door or window of a main casing, a spring thrown latch member mounted in said main casing, a rotatable means in said main casing, a cam arm on said rotatable means adapted to engage the tail of said latch-member, a handle-mechanism for actuating said rotatable means, vertical latch mechanism mounted at the ends of said meeting stile, each comprising a casing, a spring projected latch-body mounted therein, and an inwardly extending tail-body mounted at its inner end, a lever-member pivotally mounted in said main casing, an arm on said rotatable means interconnected with said lever-member for oscillating the same, connecting-rods, means for slidably supporting the outer ends of said connecting-rods, means for interconnecting the

outer ends of said connecting rods with said tail-pieces of said vertical latch-mechanisms, and coupling means at the inner end of each connecting-rod for detachably connecting the same with said pull-pieces connected with said lever-arm.

3. A combined latch and lock mechanism for doors and casement windows comprising a main casing, a spring-thrown latch-member mounted in said main casing, said latch-member having a tail-projection at its inner end, a rotatable barrel mounted in said main casing, a handle-means connected with said rotatable barrel, a second independently rotatable barrel mounted in said main casing in alinement with said first-mentioned barrel, a handle means connected with said second barrel, a coupling-tumbler mounted in said casing provided at its free end with a coupling pin, a lug on said second barrel adapted to engage said coupling pin of said coupling-tumbler, a projection on said first barrel adapted to receive the engagement of said coupling pin of said coupling-tumbler whereby the rotation of said second barrel is transmitted through said coupling-pin to said first barrel, means for removing said coupling-tumbler and its coupling-pin from operative relation to said first and second barrels, and a cam-arm on said first barrel adapted to engage said tail-projection of said latch-member.

4. A combined latch and lock mechanism for doors and casement windows comprising a main casing, a rotatable barrel mounted in said main casing, a handle-means connected with said rotatable barrel, a second independently rotatable barrel mounted in said main casing in alinement with said first-mentioned barrel, a handle means connected with said second barrel, a coupling tumbler mounted in said casing provided at its free end with a coupling-pin, a lug on said second barrel adapted to engage said coupling-pin of said coupling tumbler, a projection on said first barrel adapted to receive the engagement of said coupling-pin of said coupling tumbler whereby the rotation of said second barrel is transmitted through said coupling-pin to said first barrel, means for removing said coupling-tumbler and its coupling-pin from operative relation to said first and second barrels, and a cam-arm on said first barrel adapted to engage said tail-projection of said latch-member.

5. A combined latch and lock mechanism for doors and casement windows comprising a main casing, containing a latch-mechanism

130

nism, a rotatable barrel mounted in said main casing, latch actuating means connected with said barrel, a handle-means connected with said rotatable barrel, a second independently rotatable barrel mounted in said main casing in alinement with said first-mentioned barrel, a handle-means connected with said second barrel, a coupling-tumbler mounted in said casing provided at its free end with a coupling-pin, a lug on said second barrel adapted to engage said coupling pin of said coupling-tumbler, a projection on said first barrel adapted to receive the engagement of said coupling pin of said coupling-tumbler, whereby the rotation of said second barrel is transmitted through said coupling-pin to said first barrel, an oscillating cam mounted in said main casing, cam-projections extending upwardly from said oscillating-cam, a knob connected with said oscillating-cam for operating the same from the inner side of a door or window, one of said cam-projections being adapted to be turned into removing engagement with said coupling-tumbler to remove its coupling pin from operative relation to said first and second barrel, and a key-lock mechanism operable from the outside of said door or window to engage and operate said oscillating-cam to control the position of said coupling-tumbler.

6. The combination with the meeting

stile of a door or window, of a plurality of latch-members, a rotatable barrel, a handle-means extending from the inner side of said meeting-stile and engaging said barrel, a second independently rotatable barrel in alinement with said first barrel, a handle-means extending from the other side of said meeting-stile and engaging said second barrel, a removable coupling-tumbler, a coupling pin connected with the free end of said coupling-tumbler, means upon said second barrel engaging said coupling pin, means upon said first barrel engaged by said coupling pin, intermediate mechanism connecting said first barrel with said latch-members, whereby the rotation of said first barrel simultaneously withdraws said latch-members from their latching positions, and means for removing said coupling-tumbler and its coupling pin from operative relation to said first and second barrels, whereby said outside handle-mechanism and said second barrel are rendered inoperative to move said first barrel and said latch-members connected therewith.

In testimony, that I claim the invention set forth above, I have hereunto set my hand this 31st day of March, 1913.

CARL J. HAGSTROM.
